UNITED STATES PATENT OFFICE.

CHARLES H. SPENCER, OF BALTIMORE, MARYLAND, ASSIGNOR TO H. S. DULANEY, OF BALTIMORE, MARYLAND.

PIANO PLAYER.

1,423,271.

Specification of Letters Patent.

Patented July 18, 1922.

Application filed May 13, 1919. Serial No. 296,918.

To all whom it may concern:

Be it known that I, CHARLES H. SPENCER, a citizen of the United States of America, residing in the city of Baltimore, State of Maryland, have invented certain new and useful Improvements in Piano Players, of which the following is a specification.

In the present condition of the piano player art, a fair degree of perfection in operation having been secured, new developments relate largely to economy of space, accessibility, and a convenient arrangement of the pneumatic units which will not interfere with manual or key operation of the piano.

By this invention I have produced a new type of player, in which these objects have been accomplished and which embodies other important improvements. The player units, including the pneumatics or bellows, are mounted in the rear ends of the keys or key levers, the same being cut away for this purpose, and substituted by a frame which takes the place of the cut away portion of the keys, and within which the pneumatics are mounted, i. e., the key corresponding to each note of the piano to be operated by the player carries the bellows or pneumatic unit which operates that note.

The motion, due to the contraction of the bellows when it is connected to the wind chest, is communicated to the wippen preferably by means of a combination of levers. Normally, when the pneumatic is not in operation, the lever or member which is directly in contact with the wippen, rests on the aforesaid rigid frame, so that in manual playing as the extension frame is lifted when the key is pressed, the lever resting upon it carrying the wippen is lifted with it as a rigid structure, giving the key its ordinary effect and operation independently of the pneumatic. In other words, the presence of the pneumatic does not interfere with the operation of the keys, and the use of the keys does not interfere with the effectiveness of the pneumatic.

Further than this, applicant's pneumatic as included in the present type of player, has been redesigned and changed to include novel features and combinations of features. Particularly, the bleeder opening in the diaphragm has been many times enlarged, and the tongue which communicates the motion of the diaphragm to the valves carries a

valve member, or acts as a valve to close the bleeder opening at the desired periods, to make the operation of the diaphragm effective. This gives quicker action, which is important in repeat notes and like instances. 60

The wind chest is placed beneath the pneumatics and keys and is connected to the pneumatics by flexible rubber tubing, the connection being conveniently accessible by way of a removable bottom board. The motion of the pneumatic, which results from its connection to the vacuum in the wind chest, is communicated to the wippen by means of a series of levers which multiply the motion of the pneumatic; that is, there is an arm secured to the bottom plate of the bellows extending backward from what may be termed the pivotal or inner end of this plate. This arm at its extremity engages an upright connecting rod, which at its upper 70 end engages a lever which extends forward over the end of the key extension frame toward the fulcrum of the key, being pivoted or hinged at its forward end on the extension frame intermediately of its length. The wippen engages this lever from above, and the key frame carries a support upon which this lever rests when the bellows is in extended or inoperative position. Contraction of the bellows by connecting it to the 75 wind chest operates the note through the levers and wippen, and when the bellows is free and not so contracted, pressure on the key operates it in the ordinary way, carrying the lever which engages the wippen upward, and playing the note as if the whole structure were integral. 80

In the accompanying drawing I have illustrated a series of pneumatics embodying the various features of my invention in the 85 form in which they have been developed. 90

Figure 1 is a vertical, longitudinal section showing a key fragmentarily, and the manner of applying my player thereto, also including the details of a player unit. 100

Figure 2 is a plan view of a series of keys, fragmentarily shown, with the pneumatics operating the same.

Figure 3 is an elevation of the end of the U shaped key container frame, looking from 105 line 3, 3 of Fig. 1.

Referring to the drawing by numerals, the key 1 is shown as fulcrumed at 2 on a pivot pin 3 in the usual manner. The key as previously constructed extends backward 110

beyond and beneath the wippen at 4. In the present instance, however, the keys are cut away as indicated on the irregular line 5—5 and for the rear end is substituted a 5 closed frame 6 which may be made of a sheet metal band. Roughly speaking, this is in the form of a U lying on its side.

Within each frame is a player unit corresponding to the key to which the frame is secured, and so arranged that the frame and player unit take the place of the cut away portion of the key. Each such player unit includes a bellows or pneumatic 8 with the usual valves and passages and the means 15 for operating the valves, also the diaphragm and the diaphragm chamber. More specifically, the diaphragm chamber 9 as shown and preferably is formed in the contacting surfaces of two plates, a top plate 10 and a 20 bottom plate 11. To this plate 11 the upper stationary side 12 of the bellows is secured. The three members 10, 11 and 12 together form a rigid structure, which is fastened to the frame by screws 13 and 14, the forward end of the diaphragm chamber plate 10 being seated in the key at 15. The diaphragm chamber 9 has the flexible diaphragm 16 secured therein by clamping the edges of the fabric between the two plates or members 30 10 and 11 where they meet in the walls of the chamber. The motion of the diaphragm is communicated to the valves by means of a tongue or lever 17 pivoted at 18, the end of this tongue remote from the pivot engaging 35 the depending pin or stem 19 of the lower valve 21 of a pair of valves 21, 22 from below, the upper valve 22 being in the present instance actuated by and from the lower valve by means of a depending pin 23. 40 The regular operation of the diaphragm whereby it is caused to open the valve letting the vacuum from the wind chest into the bellows, then permitting the valve to close, is well understood, the closing of the 45 valves being alternate. The recovery of the diaphragm has ordinarily been accomplished by a small bleeder opening, which permits air to pass at all times, causing the diaphragm to recover, owing to the 50 leakage, soon after the outside air pressure is cut off. The action is not, however, quick enough to provide for repeat notes of the high frequency with which they are produced by some pianists. In the present 55 instance quicker action is provided by means of a comparatively large opening in the diaphragm in the place of the old bleeder opening, which opening is closed when the diaphragm is subject to outside pressure, 60 and opened to permit quick recovery when outside pressure is cut off. In other words, I provide a large air escape opening 24 in the diaphragm, which is closed by contact of the diaphragm with the tongue 17, shutting off the flow of air almost entirely and pre-

venting unnecessary loss, and giving quicker action by larger flow when release is desired. Preferably there is a valve or cover for the opening mounted at 25 on the tongue.

In the present instance the portion of the 70 diaphragm chamber beneath the diaphragm is connected to the corresponding point in the tracker bar by tubes 27 and the wind chest 28, which, as shown, is beneath the keys, and is connected to the upper half of 75 the diaphragm chamber by a metal and flexible connection 29 the same consisting of nipples 30 one for each unit arranged along the wind chest, corresponding elbows or nipples 31 one for each unit connected 80 to the upper half of the diaphragm chamber, and rubber tubes or unions 32 joining the nipples 30 and 31. These may be conveniently disconnected when it is desired to remove the keys, access to this portion of 85 the player being had from beneath through a hand hole or space formed by removing one of the bottom boards at 33. Leading from the bellows 8 is the passage 34. This is connected by the valve passage 90 20 to the diaphragm chamber above the diaphragm, and by a passage 35 to the outside air. Both the passage into the diaphragm chamber and the passage to the outside air are controlled by corresponding 95 valves 21 and 22, as already described. That is, when the diaphragm is up, the upper valve 22 is closed, and the lower valve 21 is open, and vice versa, connecting the bellows to the vacuum in the wind chest through 100 the diaphragm chamber and the passage 34 or to the outside air, as the case may be. It will be noted that I use an elongated diaphragm which makes it possible to get sufficient pressure to actuate the valve with 105 a very small width and to make the pneumatics of single key width so that they can be arranged one in the body of each key, as described.

The bottom side, or moving member 38 110 of the bellows swings about its forward end toward and from the top member of plate 12 which in turn is rigidly connected with the key. Secured to this bottom plate 38 is an extension arm 39 which swings in a 115 slot 40 in the end of the U-shaped frame 6. This arm 39 is connected by an upright arm 41 with a swinging lever or plate 42 the same being hinged at its forward end to the top of the frame 6 intermediately of the 120 latter. This plate 42, when the player unit is quiescent, rests on a bracket or support 43 on the extension frame 6 of the key, a leather or rubber pad 44 being preferably 125 interposed to prevent noise.

When the piano is being operated by the pneumatic player, the openings in the tracker bar over which the perforated music roll is passed in the usual manner, are connected to the corresponding pneumatics by 130

the tubes shown fragmentarily at 27. When any particular tube 27 is opened by having the aperture in the roll brought in registration with the corresponding opening in the tracker bar, the outside air is admitted to the diaphragm chamber beneath the diaphragm, and the latter is thrown up against the tongue 17 causing the air escape opening 24 in the diaphragm to be closed by contact with the tongue, which may be provided with a suitable valve or cover 25. Under any circumstances, whatever the nature of the bleeder opening, the diaphragm is raised and raises the tongue, opening the lower valve 21 and closing the upper valve 22 so that the bellows or pneumatic is cut off from the outside air and connected to the vacuum in the wind chest 28, connection being from the wind chest to the upper section of the diaphragm chamber and via valve passage 20 controlled by valve 21 to the passage 34 which in turn leads to the bellows. This connection to the vacuum in the wind chest contracts the bellows, lifting the lower plate 38 with the arm 39, the upright rod 41 and the hinged arm 42 which has been resting on the bracket 43 rigid with the key extension frame 6. The wippen 4, being in immediate contact with the arm 42 is likewise raised, causing the note to be played. In this connection the combination of levers 39, 41, 42 by which the motion of the bellows is communicated to the wippen is considered of importance also the manner of controlling the flow of air through the air escape or equalizer. It should be noted that while in the ordinary arrangement the bleeder opening is made small so that it is actuated by change of connections, as desired, it is never closed, the leakage of air being continuous so long as there is a difference of pressure on the two sides of the diaphragm. The present arrangement, in which a means for closing the bleeder opening is provided, saves the air which previously passed through the diaphragm during the operation of the pneumatic and gives quicker recovery, because the means for closing the bleeder opening during the operation of the pneumatic makes it feasible to provide a larger opening with a quicker flow of air and a quicker recovery of the diaphragm, which in turn provides for the playing of quicker repeat notes than with the old device. When the opening in the tracker bar is closed, outside air pressure is removed from the diaphragm, which permits it to relax, opening the bleeder, which immediately equalizes the pressure, dropping the tongue 17, closing the lower valve 21, and opening the upper valve 22, which in turn admits the outside air to the inside of the bellows, and distends it, dropping the bottom plate 8 and the arm 39 and the wippen, until the arm 42 directly in contact with the wippen

rests on the bracket 43 integral with the key frame 6.

During manual playing the wippen is directly supported upon the key frame or operating arm 42 resting directly upon the key frame, so that the manual operation of the piano by the keys is in no way affected by the presence of the piano player apparatus.

The removal of the keys is an ordinary manually operated piano is known to be a very slight undertaking; it is practically only necessary to lift them up and withdraw them from beneath the front board. When the present player is installed, one of the bottom boards beneath the keys is made removable, providing an opening 33 so that to remove a player unit it is only necessary to take the board from the opening 33, disconnect the rubber tube 32 and the tracker tube 27 and lift the key with the pneumatic out of the piano in exact accordance with the old practice in removing the keys.

I have thus described a player embodying my invention, specifically and in detail, in order that the nature and operation of the device may be well understood and those skilled in the art may be enabled to practice the invention; however, the specific terms herein are used in the descriptive rather than in the limiting sense, and the scope of the invention is defined in the claims:

What I claim is:

1. The combination of a piano action and a key a pneumatic unit, including a bellows, valve passages, valves and valve actuating means, and a support for the player unit rigid with the key, whereby the player unit and support form the rear portion of the key.

2. The combination of a piano action and key a pneumatic unit, including a bellows, valve passages, valves and valve actuating means and a support for the player unit integral with the key, whereby the player unit and support form the rear portion of the key, a combination of levers connected to the moving member of the bellows, one of said levers engaging the wippen from beneath and means carried by the key for communicating the key action to the wippen when the pneumatic player is inoperative.

3. The combination of a piano action and key the rear end of the key being in the form of a support for a pneumatic unit, a pneumatic unit mounted on said support to move with the key, the unit consisting of a bellows with valves, passages, means for actuating the valves, and means for communicating the key motion to the wippen when the pneumatic is inoperative.

4. The combination of a piano action and key the rear end of the key being in the form of a support for a pneumatic unit, a

pneumatic unit on said support in alignment with the key and taking the place of the rear end of the key as ordinarily constructed, the pneumatic unit including a bellows, 5 air passages, valves controlling the passages, means for operating the valves and suitable connection means communicating the motion of the bellows to the corresponding wippen and means carried by the key 10 for communicating the key motion to the wippen when the pneumatic is inoperative.

5. In a pneumatic piano player, a player unit comprising a bellows, air passages, valves controlling the passages, a diaphragm 15 for operating said valves to connect the bellows to the outside air and the vacuum alternately, the diaphragm having an air escape opening, means for closing said opening when pressure is applied to the dia- 20 phragm to operate the valves and connect the bellows to the vacuum and uncovering it when the pressure is removed.

6. In a pneumatic piano player, a player unit including a bellows, the diaphragm

chamber, air passages connecting the bellows to the outside air and to the diaphragm chamber, the latter being connected on one side to the tracker bar and on the other side of the diaphragm to the wind chest, valves controlling said passages means for communicating the motion of the diaphragm to the valves, an air escape opening in the diaphragm and a cover for said opening carried by said last named means.

7. The combination with a piano action 35 and keys, of pneumatic units, each including bellows, air passages, valves, and an elongated diaphragm for actuating same, the pneumatics being each mounted in the corresponding key to move therewith. 40

8. A piano key having a pneumatic unit wholly embodied therein to move therewith.

Signed by me at Baltimore, Maryland, this 6th day of May, 1919.

CHARLES H. SPENCER.
